UNITED STATES PATENT OFFICE.

EDWARD G. LOCKE, OF CHICAGO, ILLINOIS.

DESIGN FOR A BADGE.

SPECIFICATION forming part of Design No. 20,365, dated December 2, 1890.

Application filed October 30, 1890. Serial No. 369,860. Term of patent 7 years.

To all whom it may concern:

Be it known that I, EDWARD G. LOCKE, a citizen of the United States, residing at Chicago, in the county of Cook and State of Illinois, have invented and produced a new and original Design for Badges, of which the following is a specification, due reference being had to the accompanying drawings, forming part thereof, wherein—

Figure 1 represents a face or front view of the badge, and Fig. 2 a similar view of the reverse side of the badge.

The leading feature of my design consists of a circular portion A, bearing within its center a representation of the globe, exhibiting the Western Hemisphere, the globe being encircled by two concentric rings, between which is a space for suitable words, as "World's Columbian Exposition," and the date "1893." This circular portion A is shown

as suspended by a representation of the United States flag B, which in turn is shown as depending from a bar C. Upon the reverse side of the badge the circular portion A contains within its center a representation or illustration of a block house intended to represent Fort Dearborn, and within the two concentric circles surrounding the same is a space for suitable words, as "Fort Dearborn, Chicago, 1833." The reverse side of the flag B and bar C correspond with the front side of the same.

What I claim is—

The design for a badge as herein shown and described.

EDWARD G. LOCKE.
